UNITED STATES PATENT OFFICE.

ROBERT B. WASSON, OF CRANFORD, NEW JERSEY.

MACHINE FOR PRODUCING END CLEARANCE OF PISTON-RINGS.

1,264,461.

Specification of Letters Patent. Patented Apr. 30, 1918.

Application filed March 24, 1916. Serial No. 86,376.

To all whom it may concern:

Be it known that I, ROBERT B. WASSON, a citizen of the United States, residing in Cranford, Union county, State of New Jersey, have invented certain new and useful Improvements in Machines for Producing End Clearance of Piston-Rings, of which the following is a specification.

The object of this invention is a machine for producing an approximately predetermined end clearance in piston rings of internal combustion and other engines. It will be understood that these rings are divided and have their ends separated by a substantial distance, and that in order to introduce them within the cylinder it is necessary to compress them, thereby causing their ends to approach. Under working conditions, the rings become heated and expand, thereby bringing their ends still closer together. It is essential, however, that the ends do not bear against each other, because this would cause the ring to press with undue force against the confining cylinder wall, causing unnecessary wear and loss of power, and eventually destroying the bore of the cylinder. On the other hand, it is important that any space between the ends of the rings when performing their functions be as little as possible, in order to avoid unnecessary loss of compression of the charges through leakage. The theoretically ideal condition would be one in which the ring ends under working conditions would barely touch without pressure. Because of unavoidable variations in machinery and operations in the engines themselves, however, it is impossible to realize this condition. It is, therefore, necessary to provide the rings with an amount of end clearance sufficient to insure that in spite of variations the ends of the rings when in use will not touch. For the reason given, however, the clearance should be no larger than is necessary to take care of all the possible factors. The first factor which may be considered is the maximum linear heat expansion of the ring when the engine is running. Another factor is variation in the diameters of the rings, for it is obvious that a ring which is finished of somewhat larger external diameter than another, other things being equal, will have to be compressed more in getting it into the cylinder and therefore have its ends brought closer together than

will be the case with the other, slightly smaller ring. Manifestly, also, if the bore of the cylinder is slightly larger or smaller than normal, the degree of approach of the ring ends will be affected. The possible variations may be compensative or additive, but the latter condition must be assumed and provided for, and in addition a further reasonable allowance must be made as a factor of safety. The actual amount of clearance to satisfy these requirements naturally differs for different sizes of rings, but may be ascertained in any particular case. The present machine affords the means for providing an approximately exact end clearance in rings of a given size or given range of sizes. Furthermore, the trimming of ends of the rings is performed by a tool of such form that the end faces of the rings are substantially parallel under the average working condition. The machine disclosed herein is designed for carrying out the method constituting the subject-matter of co-pending application filed even date herewith, Serial No. 86,377. The particular machine disclosed herein is adapted to operate upon rings in which the ends are cut obliquely, but the invention is not necessarily so limited. The preferred embodiments of the machine will now be briefly described, but it is understood that the invention is not confined to the precise construction shown and that numerous changes, omissions, additions and reversals within the scope of the appended claims are permissible.

In the drawings illustrating the said preferred embodiment:

Figure 1 is a view of an embodiment of the machine partly in end elevation and partly in vertical section;

Fig. 2 is a plan view of the machine with parts in horizontal section;

Fig. 3 is a vertical longitudinal section through the machine, the clamp and its mounting being removed for purpose of clearness;

Fig. 4 is a vertical section taken in the plane of the axis of the cutter, parts at the center being shown in elevation;

Fig. 5 is a semi-diagrammatic side view illustrating the relation of the ring, the cutter and the gage at the commencement of operations;

Fig. 6 is a view of the same parts, show-

105

110

ing the cutter and gage in horizontal section and the ring in plan;

Fig. 7 is a section taken on the line 7—7 of Fig. 5; and

5 Fig. 8 is a detail enlarged sectional view showing the adjustable pivot mounting for the clamp.

The machine has a suitable bed 1, upon which is mounted an adjustable table 2. The latter is adjustable vertically and horizontally, that is to say in two directions at right angles to each other. The vertical adjustment may be secured by means of inclined or wedged surfaces 3 on the bottom 10 of the table and on the bed, whereby movement of the table lengthwise of these surfaces effects an accurate raising or lowering, as will be readily understood. The vertical adjustment may be locked by set screws 4, 15 threaded through overhanging stationary ledges 5 to bear upon the top of the table. The horizontal adjustment is provided for by means of reversed wedges 6, which are interposed between the sides of the table 2 20 and the opposed walls of the bed, these wedges being locked in position by means of screws 7.

Upon the table 2 is a slidable feed carriage 8, the bottom of which is shown as 25 formed with a dove-tailed guide portion 9 entering a similar guideway in the table. It will be observed that the direction of movement of the carriage 8 on the table 2 is at right angles to the vertical and trans- 30 verse adjustments of the latter.

In this instance the feed carriage supports the ring-holding means, so that the ring is fed to the cutter 10, presently to be described, but a reversal of this condition 40 is not excluded.

The ring-holding means comprises a chuck 11 and a clamp 12. The chuck 11 is mounted movably in a housing or superstructure 13 supported on and movable with the carriage 8, and is provided with a circular internal ring seat 14 of predetermined diameter, this diameter being greater than the diameter of the cylinder which the ring to be acted upon is designed to fit, but less 45 than the diameter of the ring when unconfined, so that the ring is compressed part way when inserted in the chuck. In order that the machine may accommodate a variety of sizes of rings, the chuck 11 is made 50 removable from the housing, so that it may be replaced by any one of a number of other chucks having ring seats of different predetermined sizes. For the same reason the clamp 12 which holds the ring rigidly 55 against its seat is made conical or substantially conical. This formation of the clamp also insures the ring being held tightly at all points against the inner circular wall 60 of the chuck.

65 The mounting for the clamp 12 is of such

character that the clamp may center itself with respect to the rings, and may readily be moved into and out of operative position. In the particular construction shown, an arm 15 is pivoted at one end upon a 70 frame piece 16 fixed to the face of the housing 13, and intermediate its ends carries a spindle 70 which carries the clamp 12 and may be advanced by a screw 17 having a handle 18. On the lower or inner end of 75 the said spindle is a nut 19 locked by another nut 20 and having a spherical surface 21 fitting a spherical recess in the clamp. The nut 19 passes through a central opening in the clamp communicating with said 80 recess, and is externally threaded to receive a nut 22, between which and the spherical surface 21 the clamp is confined. Sufficient looseness is provided so that the clamp can rock upon its spherical bearing in order to 85 adjust itself to a uniform bearing upon the ring.

The operating screw 17 has threaded engagement in a bushing 23, which is fixed in the arm 15 and which also constitutes a 90 housing for a spiral spring 24. The said spring bears at one end upon a cap 25 on the end of the said housing, and at the other end against a shoulder 26 on the spindle 70. The upper or outer end of the spindle enters 95 a bore in the screw 17, where a ball 27 is provided for the purpose of reducing the friction of end thrust. It will therefore be understood that the spindle, and thereby the clamp 12, is forced inward against the 100 ring by means of the screw 17 and is retracted by the spring 24 when the screw is eased off. However, it will be understood that these specific details may be varied. A pin 28 projecting from the arm 15 and 105 passing loosely through an opening in the clamp 12 holds the latter against rotation. The arm and the clamp are held in operative position by means of a latch 29, mounted pivotally on the frame piece 16 and 110 having a hooked end to engage a lip 30 on the free end of the arm. The latch is held yieldingly in locking position by a spring 31, and may be released by finger pressure on its handle portion 32. 115

Both the chuck 11 and the clamp 12 are provided with slotted entrances 33 and 34, respectively, to receive the cutter 10, and it is for the purpose of preventing the slot in the clamp from being disposed out of 120 alignment with the cutter that the guide-pin 28 is provided.

The arm 15 and with it the clamp 12 are adjustable sidewise relatively to the chuck 11, in order that the clamp may be positioned coaxially with the ring seats of different chucks 11 which may be inserted in the housing 13. To this end the lower or pivotal portion of the arm 15 is mounted 125 rotatably on a bushing 35 (see Fig. 8) 130

which is internally threaded so that it may be shifted along a screw rod 36 mounted in lugs 37 on the frame piece 16. This is accomplished by applying a wrench to a hexagonal head 38 on one end of the bushing. At the other end of the bushing a nut 39 threaded on the rod holds the arm 15 in place. A lock nut 40 is provided for rendering the adjustment secure. The catch 29 has a similar adjustable mounting on a bushing 41 on its screw-threaded rod 42.

To insert a ring α in the holder, the clamping screw 17 is eased off. The catch 32 is swung out of engaging position, and the arm 15 with the clamp 12 are then moved away from the chuck. The ring to be operated upon is then introduced into the seat in the chuck 11, the arm 15 is swung toward the chuck, the catch 29 is engaged with the lip 30, and then by turning the screw 17 the ring is pressed against the seat and at the same time the reaction locks the lip 30 against the hook of the catch 29.

In the embodiment of the invention illustrated, the tool 10 consists of a rotary milling cutter, which tapers from its central portion to the periphery and is provided on both sides with cutting edges 43, so as to operate simultaneously upon both ends of a ring. Cutting edges 44 are also preferably formed on the periphery of the disk, since its thickness at the circumference may be greater than the distance between the ends of the ring in the holder. The tapering of the cutter is for the purpose of leaving the ends of the ring at such an angle that, when the ring is confined under average working conditions, the end faces will be substantially parallel. The specific angle of the cutter to secure this result should be varied for different sizes of rings.

The cutter disk is mounted on the end of a shaft 45, bearing at its opposite ends fast and loose pulleys 45^a and 45^b for the reception of a driving belt. The shaft is journaled by means of cone bearings 46 in corresponding bushings 47 within a housing 48 secured to the bed. One of these bushings has threaded engagement with the housing at 49 in order that it may be advanced to take up wear, and is adapted to be locked by a nut 50. The cutter is held on the projecting end of the shaft between nuts 51 and 52, which permit the position of the cutter on the shaft to be adjusted in reference to a gage 53. The latter stands in front of the edge of the cutter, where it operates upon the ring, and is therefore adapted to enter the latter in advance of the cutter. It is preferably formed by a ring, which is thinner than the edge of the cutter and is applied by screws 54 to the face of the housing 48.

In the manufacture of a ring wherein the solid ring is split and hammered, as in my

Patent No. 1,009,000, dated November 14, 1911, the ends of the ring separate and may also be left in a somewhat unfinished condition so that on being compressed to the working diameter these ends are not quite parallel. This condition may be corrected by the present machine.

In order to enable the machine to operate upon rings which are cut at an angle (usually at an angle of 30°), the ring-holding means and the cutter are disposed in planes which are oblique to each other. Preferably the cutter is vertical as shown, while the ring chuck and clamp are mounted at an appropriate inclination on the feed carriage 8.

In the operation of the machine it is desirable for accurate work that the center of the diameter of the ring, the center of thickness of the ring and the center of thickness of the cutter be aligned with the direction of the feeding movement. This is provided for in this machine by the two relative adjustments between the cutter and ring-holder at right angles to the movement of the slide carriage 8.

Suitable means are provided for effecting the feeding movement of the carriages. In the particular construction shown a hand lever 55 is fulcrumed at 56 on the bed 1 and connected by a slot in one of its ends with a pin 57 held in a clevis 58 secured to one end of the carriage. With a tapered cutter the amount of metal which is removed from the ring in providing the end clearance is determined in part by the extent of the feeding movement. For this reason a stop 59, conveniently in the form of a screw having a lock nut 60, is provided so as to terminate the forward feed movement at an exactly predetermined point.

To operate the machine the feed carriage 8 is withdrawn from the cutter, the clamp 12 is moved with the arm 15 outward from the chuck, a ring is inserted in the chuck 11 with its opening opposite the entrance 33, the arm 15 is swung back into place, and the clamp forced home against the ring. Before this is done, the opening in the ring is accurately positioned opposite the cutter by means of the gage 53, which enters the opening as shown in Figs. 5 and 6. The carriage is now advanced in order to feed the open portion of the ring against the rapidly revolving cutter. The latter removes a small amount of metal simultaneously from both ends, the width of the resulting end clearance depending upon the following factors, namely, the internal diameter of the ring seat of the chuck (which determines the distance between the ring ends before the cutter is brought into action), the angle and thickness of the cutter, and the extent of the feeding movement as determined by the stop 59. The diameter of the ring seat, it may

be noted, must be somewhat greater than the cylinder bore for which the ring is designed, since otherwise the cutter would have to be too thin to be practicable. There must, however, be a relation between the factors indicated, in order that the proper amount of metal may be removed. Naturally, any one of the factors may be varied, compensating variations being made in the others, and, 10 of course, the precise proportions will have to be changed to suit different sizes of rings. The desired amount of metal having been removed, the feed carriage is returned to its starting position, the corrected ring is removed, and a fresh one inserted preparatory to being advanced against the cutter.

The machine may be easily adjusted to operate upon rings of different sizes by changing the chuck and cutter, of which a 20 series will preferably be provided with each machine. The same cutter may be used for producing end clearance in different sizes of rings, if eventual parallelism between the faces of the clearance slot is not required.

25 For any given size of ring, a greater or less amount of end clearance may be produced by adjusting the stop 59 so as to permit of a greater or less degree of feeding movement, that is to say to cause the cutter to pass into 30 the interior of the ring a greater or less distance.

What I claim as new is:

1. A machine for producing end clearance of divided piston rings, comprising a chuck 35 and means for clamping a divided ring unyieldingly therein at a predetermined degree of confinement, means adapted to operate between the ends of the ring to remove metal therefrom, and means for producing accurate relative feed between said metal-removing means and ring-chuck.

2. A machine for producing end clearance of piston rings, comprising a chuck and means for clamping a divided ring unyieldingly therein at a predetermined degree of confinement, and mechanism for operating at both ends of the ring simultaneously to produce an approximately predetermined clearance therebetween.

50 3. In a machine for producing end clearance of piston rings, the combination of a chuck having a ring seat of predetermined diameter, a ring-clamping member adapted to act outwardly upon the ring, a tapered cutter adapted to operate upon the ends of the ring, means for driving the cutter, means for relatively feeding the cutter and ring-holder, and means for accurately determining the amount of such feed.

60 4. In a machine for producing end clearance of piston rings, the combination of a chuck and means for clamping a divided ring unyieldingly therein at a predetermined degree of confinement, the chuck having an entrance through its side, a driven

cutter disk adapted to operate through said entrance between the ends of the ring, and means for producing accurate relative feed between the ring-chuck and disk.

5. A machine for producing end clearance 70 of piston rings, comprising the combination of a chuck and means for clamping a divided ring against movement therein and with a predetermined degree of confinement, and a driven cutter having cutting edges 75 upon both side faces to operate between the ends of the ring.

6. In a machine for producing end clearance of piston rings, the combination of a chuck and means for clamping a divided 80 ring against movement therein and with a predetermined degree of confinement, and a tapered rotary disk having cutting edges on the side faces adapted to operate upon both ends of the ring simultaneously. 85

7. In a machine for producing end clearance of piston rings, the combination of a chuck and means for clamping a divided ring against movement therein and with a predetermined degree of confinement, a 90 driven tool adapted to operate upon the ends of the ring, and a gage opposite the edge of the tool to aline the opening in the ring therewith.

8. In a machine for producing end clearance 95 of piston rings, the combination of a chuck and means for clamping a divided ring against movement therein and with a predetermined degree of confinement, a driven tool adapted to operate upon the 100 ends of the ring, means for relatively feeding the tool and ring-chuck, means for accurately determining the amount of such feed, and a gage mounted with and in front of the tool to enter the opening in the ring. 105

9. A machine for producing end clearance of piston rings comprising the combination of a chuck and means for clamping a divided ring against movement therein and with a predetermined degree of confinement and a cutter having a predetermined 110 taper for removing metal from the ends of the ring so that the ends of the ring when compressed will be substantially parallel.

10. A machine for producing end clearance of piston rings comprising the combination of a chuck and means for clamping a divided ring against movement therein and with a predetermined degree of confinement, a gage entering the opening of the ring, and a cutter having a predetermined taper for removing metal from the ends of the ring so that the ends of the ring when compressed will be substantially parallel. 115 120 125

11. In a machine for producing end clearance of piston rings, the combination of a chuck and means for clamping a divided ring against movement therein and with a predetermined degree of confinement, a 130

driven cutter adapted to operate upon the ends of the ring, means for relatively feeding the ring-chuck and cutter, means for accurately determining the amount of such feed and means for alining the centers of the ring and cutter with the direction of feed.

12. In a machine for producing end clearance of piston rings, the combination of a 10 chuck and means for clamping a divided ring unyieldingly therein at a predetermined degree of confinement, a driven cutter adapted to operate upon the ends of the ring, means for producing accurate relative feed between the ring chuck and cutter, and means for producing relative adjustment between the ring-chuck and cutter in two directions at right angles to each other and to the direction of the feed.

13. In a machine for producing end clearance of piston rings, the combination of a holder adapted to hold a ring at a predetermined degree of confinement, a rotary driven disk adapted to operate between the ends of the ring, said disk and ring held by said holder being oblique to each other, means for producing accurate relative feed between the disk and ring-holder, and means for relatively adjusting the ring-holder and disk at right angles to the direction of feed.

14. In a machine for producing end clearance of piston rings, the combination of a holder adapted to hold a ring at a predetermined degree of confinement, a tapered tool 35 adapted to operate between the ends of the ring, means for producing relative feed between the ring-holder and tool, and means for predeterminedly limiting said feed.

15. In a machine for producing end clearance of piston rings, the combination with 40 a tool adapted to operate in the opening of a ring to remove metal from the ends thereof, of a table, a feed carriage movable on and relatively to the table toward and from the 45 said tool, means for accurately determining the amount of feed, a chuck on said carriage and means for clamping the ring unyieldingly therein at a predetermined degree of confinement, and means for adjusting said 50 table at right angles to the direction of feed movement.

16. In a machine for producing end clearance of piston rings, the combination of a 55 rotary driven cutter having lateral cutting edges, a table, a feed carriage movable on and relatively to the table toward and from the said cutter, means for accurately determining the amount of feed, a chuck on said carriage and means for clamping a ring unyieldingly therein at a predetermined degree of confinement, and independent means 60 for adjusting said table vertically and horizontally, transversely of the direction of feed.

17. In a machine for producing end clear-

ance of piston rings, the combination with a member adapted to operate in the opening of a ring to remove metal from the ends thereof, of a holder for the ring comprising a chuck having a ring seat of predetermined size, and a conical clamp adapted to enter 70 the ring and hold the same against the said seat.

18. In a machine for producing end clearance of piston rings, the combination with 75 a member adapted to operate in the opening of a ring to remove metal from the ends thereof, of a holder for the ring comprising a chuck having a ring seat of predetermined size, a conical clamp adapted to enter 80 the ring and hold the same against the said seat, and means for supporting said clamp with freedom to find its own center in the ring to be held.

19. In a machine for producing end clearance of piston rings, the combination with 85 a member adapted to operate in the opening of a ring to remove metal from the ends thereof, of a holder for the ring comprising a chuck having a ring seat of predetermined size, and means for holding a ring to the said seat comprising a conical clamp, a spindle having a spherical bearing for said clamp, and a movable support for the spindle enabling the clamp to be moved 90 into and out of operative position.

20. In a machine for producing end clearance of piston rings, the combination with 100 a member adapted to operate in the opening of a ring to remove metal from the ends thereof, of a holder for the ring comprising a chuck having a ring seat of predetermined size, and means for holding a ring to the said seat comprising a clamp, a hinged support for the clamp enabling the same 105 to be moved into and out of operative position, and means for forcing the clamp against the ring.

21. In a machine for producing end clearance of piston rings, the combination 110 with a member adapted to operate in the opening of a ring to remove metal from the ends thereof, of a holder for the ring comprising a chuck having a ring seat of predetermined size, and means for holding a ring to the said seat comprising a clamp, a hinged support for the clamp enabling the same to be moved into and out of operative 115 position, means for locking the said support, and means for forcing the clamp 120 against the ring.

22. In a machine for producing end clearance of piston rings, the combination with 125 a member adapted to operate in the opening of a ring to remove metal from the ends thereof, of a holder for the ring comprising a chuck having a ring seat of predetermined size, and means for holding a ring to the said seat comprising a movable support, a spindle carried thereby, a conical 130

clamp on the spindle, and screw means acting upon the spindle for forcing the clamp against the ring.

23. In a machine for producing end clearance of piston rings, the combination with a member adapted to operate in the opening of a ring to remove metal from the ends thereof, of a holder for the ring comprising a chuck having a ring seat of predetermined size, and means for holding a ring to the said seat comprising a hinged support, a latch for holding said support in operative position, a screw-operated spindle on the support, and a conical clamp having a spherical bearing on the spindle.

24. In a machine for producing end clearance of piston rings, the combination with a member adapted to operate in the opening of a ring to remove metal from the ends thereof, of a holder for the ring comprising a removable chuck provided with a ring seat, means for holding a ring to the said seat comprising a conical clamp, a movable support enabling the said clamp to be moved into and out of operative position, and means for adjusting said support transversely with relation to the chuck.

25. In a machine of the character described, the combination with a tapered tool adapted to operate between the ends of an open ring, and means for driving the tool, of a chuck having a seat for the ring and an entrance for the tool, and a clamp for

forcing the ring outwardly against said seat and also formed to permit the entrance of the tool.

26. In a machine of the character described, the combination with a tapered tool adapted to operate between the ends of an open ring, and means for driving the tool, of a chuck having a seat for the ring and an entrance for the tool, a clamp for forcing the ring outwardly against said seat and also formed to permit the entrance of the tool, and means to prevent the clamp from turning about its axis.

27. In a machine of the character described, the combination with a tapered tool adapted to operate between the ends of an open ring, and means for driving the tool, of a chuck having a seat for the ring and an entrance for the tool, a clamp for forcing the ring outwardly against said seat and also formed to permit the entrance of the tool, a movable support for the clamp including a spindle on which the clamp is mounted, and means to prevent the clamp from turning.

In testimony whereof I have signed my name to this specification, in the presence of two subscribing witnesses.

ROBERT B. WASSON.
